UNITED STATES PATENT OFFICE.

THOMAS O'DONNELL, OF IRONWOOD, MICHIGAN.

ELECTRIC FILAMENT-LAMP.

1,168,411.

Specification of Letters Patent. Patented Jan. 18, 1916.

Application filed November 6, 1914. Serial No. 870,570.

To all whom it may concern:

Be it known that I, THOMAS O'DONNELL, a citizen of the United States, residing at Ironwood, in the county of Gogebic and State of Michigan, have invented certain new and useful Improvements in Electric Filament-Lamps, of which the following is a specification.

My invention relates to improvements in electric filament lamps.

An important object of the invention is to provide means whereby the candle power of the electric lamp may be greatly increased, without a corresponding increase in the cost of the manufacture of the same.

A further object of the invention is to provide an electric lamp of the above mentioned character, which is simple in construction, inexpensive to manufacture, and convenient in use.

Other objects and advantages of the invention will be apparent during the course of the following description.

As is well known, the ordinary electric filament lamp comprises a bulb, within which is arranged a single filament support or carrier, having the filament strung thereon. In such a lamp, it is customary to connect the lead-in wires with the filament by means of short sections of platinum wire. The lamp further comprises a socket element to be screw-threaded into a stationary supporting socket element. It is obvious that the most expensive parts of the electric lamp are the platinum wires and socket element. Electric lamps thus constructed are restricted in their candle power, for certain sizes, and when more light is needed, an increased number of lamps are used.

By my construction, an electric lamp is provided which is capable of producing the candle power of two or more electric lamps having filaments and sockets of corresponding size. In my lamp, the filament frame or support is arranged within the bulb, and carries any suitable number of laterally spaced longitudinally extending branches or arms, over two, depending upon the candle power desired. The separate filaments of two or more electric lamps are thus combined in one lamp, such filaments being strung upon the longitudinal arms.

The advantage of my construction is that while a plurality of separate filaments are used, only two lead-in wires, the connecting

platinum wires, and a single socket are required, whereby the cost of manufacture of my lamp does not substantially exceed the cost of the ordinary electric lamp having a filament of a corresponding size, and is greatly below the cost of a corresponding number of lamps, required to produce the candle power of my lamp.

In the accompanying drawings forming a part of this specification and in which like numerals are employed to designate like parts throughout the same,

Figure 1 is a side elevation of a lamp embodying the invention, Fig. 2 is a plan view of the filament support or carrier, and Fig. 3 is an enlarged side elevation of one longitudinal arm or branch of the filament support or carrier.

In the drawings wherein for the purpose of illustration is shown a preferred embodiment of my invention, the numeral 22 designates a bulb, having a reduced neck 23. The numeral 24 designates the filament frame or carrier, to which is attached a cross-head 25, carrying arms or branches 26, pivoted thereto as shown at 27. Each branch 26 has a knee joint connection with the cross-head, whereby the same may be swung inwardly and is positively prevented from swinging outwardly beyond a predetermined distance. Each arm 26 is automatically swung outwardly upon being released by a leaf-spring 28 secured to the cross-head, as shown at 29. Strung upon the arms or branches 26 are filaments 30, as shown.

The support 24 is attached to a glass tube 31, containing the lead-in wires 32, connected with short platinum wires 33, in turn connected with the filaments to supply current thereto. The filaments are shown as connected in parallel, while it is to be understood that they may be connected in series if desired. The tube 31 carries an annular flange 34 adapted to be fused to the neck 23 forming an air tight connection therewith. The lead-in wires 32 are connected with contacts 31' and 31'', carried by the neck 23, as shown.

In the manufacture of the lamp, the support 24 attached to the tube 31, and carrying the arms 26, is arranged adjacent the neck 23. The arms 26 are now swung inwardly or collapsed by a suitable tool whereby they may be passed through the neck. When arranged within the bulb, the arms are released

whereby they automatically move to the outer position. The flange 34 is then fused to the neck 23, and the vacuum created in the bulb in the usual manner.

5 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

15 1. As an article of manufacture, an electric lamp, comprising a bulb having a contracted neck, a filament support adapted to extend into the bulb, extending arms pivoted

to the support and extending longitudinally of the bulb, and filaments strung upon the 20 arms.

2. As an article of manufacture, an electric lamp, comprising a bulb having a contracted neck, a filament support adapted to be extended into the bulb, longitudinally 25 extending arms pivoted to the support to swing outwardly for a predetermined distance, springs to automatically swing the arms outwardly, and filaments strung upon the arms.

In testimony whereof I affix my signature in presence of two witnesses.

THOMAS O'DONNELL.
